COMBINATION SIREN WHISTLE

Filed Jan. 26, 1931

ATTORNEY.

UNITED STATES PATENT OFFICE

FRANK WILCOX, OF LOS ANGELES, CALIFORNIA

COMBINATION SIREN WHISTLE

Application filed January 26, 1931. Serial No. 511,177.

This invention relates to a sound device which embodies both the features of a siren and a whistle, and has been designed primarily for use in directing traffic, but may find usefulness in other fields.

In directing traffic, it often occurs that the traffic officer has need for both the traffic whistle and the siren. Heretofore it has been necessary to depend entirely upon the whistle, or upon two separate devices. It, therefore, becomes a primary object of this invention to provide a single device which optionally may be made operable as a traffic whistle or as a siren. As a means toward this end, I provide a sound device having a valve embodied therein which may be utilized to instantly convert the device into a traffic whistle or a traffic siren.

In the device the same mouth piece with the same air inlet is used to operate both the whistle and the siren, and a unique manually operated cup-shaped slide valve is incorporated in a manner whereby the whistle may be optionally converted into a siren or vice versa. Accordingly, it becomes a further object of the invention to provide a valve of the character described for the purpose described.

Another object of the invention is to provide a device of the character described having a neat workmanlike appearance, and one in which the parts may be readily assembled and disassembled for cleaning purposes.

Other objects and advantages will become apparent as the description proceeds in conjunction with the drawing in which—

Fig. 1 is a perspective showing my device as it would appear complete;

Fig. 2 is a section taken substantially on the line 2—2 of Fig. 1, showing the position of the parts whereby the device operates as a siren;

Fig. 3 is the same as Fig. 2 with the parts arranged to operate as a whistle; and

Fig. 4 is a view taken substantially on the line 4—4 of Fig. 1.

In the drawing, I have illustrated my device as comprising a casing, generally designated A, having a tubular extension thereon, generally designated B. The casing A is formed with an aperture 10 and a circular

portion 11 which extends into a substantially flat portion 12 having an air inlet 13. The flat portion 12 is adapted to form the mouth-piece, and the circular portion 11 contains a valve which is operable to alternately convert the device into a whistle or a siren. 55

I have shown the valve as comprising a cup-shaped valve member 14 adapted to rotatably fit within the interior of the circular portion 11. The cup-shaped member comprises a circular wall 15 and a bottom transverse wall 16, the bottom wall 16 being provided with a series of apertures 17. 60

As best shown in Fig. 4, the member 14 forms an air-tight sliding fit within the circular portion 11, and the bottom member 16 is adapted to slide against a member 18 which closes one side of the circular portion 11. The member 18 is also provided with a series of openings 19 arranged to coincide with the openings 17 upon rotation of the cup-shaped member 14. As shown, the member 18 is press-fitted into one open end of the circular portion 11. I may use this structure, or the member 18 may be integral with the casing A. 70 75 For purposes of economy, I prefer to form the member 18 as indicated. The member 18 is further provided with an upstanding outwardly extending annular flange 20 adapted to frictionally receive on the outer periphery 80 thereof the tubular extension B, said tubular extension having openings 21 in the outer end to emit the sounds produced by a siren C to be presently described. The tubular extension B functions as a sounding board for 85 amplifying the siren sound produced, as well as a means of protecting the siren mechanism.

Within the inner periphery of the flange 20 I mount the siren generally designated C; 90 the structure in this instance comprising a yoke member 22 having a base plate 23 extending across and spaced from the member 18 to provide a space 24.

The plate 23 is provided with openings 25 95 which are adapted to pass air into sloping openings 26 in the member 27 rotatably mounted upon a spindle 28, the spindle 28 being journaled upon needle points 29 and 30 and an adjustable screw 31 being provided 100

for regulating the bearing of the spindle 28.

It is clear that as air passes through the openings 17, 19, and 25 the member 27 will revolve and produce a siren sound. The oppo-

site end of the tubular portion 11 is closed by a plate 32 which may be press fitted into place or attached in any other suitable manner.

As a means of rotating the valve member 14, I provide a slot 33 in the circular portion 11 and mount a pin 34 in the wall 15 of the member 14 in a manner to extend through the slot, and for convenience of operating I incorporate a hub 35 on the outer 10 end of the pin, and equip said hub with a ring 36 for purposes of handling the device.

In order to render the cup-shaped member 14 operable as a valve between the whistle and the siren, I form an opening 37 in the 20 wall 15 of said member.

As shown in Fig. 2, the valve is set to operate as a siren and in this position the opening 37 admits air into the member 14 which, by virtue of the closure 32 and the bottom 25 plate 16, forms a chamber 38. In this position the openings 17 register with the openings 19 and provide a clear passage for the air to the member 27.

To operate the device as a whistle, the 30 member 14 is rotated within the circular portion 11 by means of the hub 35 or the ring 36 until the opening 37 registers with the opening 10 in the casing A. It is to be observed that the opening 37 is of slightly greater 35 width than the opening 10 and provides a slit 39 for admitting air into the chamber 38. This will be recognized as a means of producing a whistle.

In order to provide the particular type of 40 whistle desired for directing traffic, I introduce into the chamber 38 a ball member 40 which may be of any suitable substance, preferably cork.

By making the slot 33 of proper dimensions 45 with respect to length, I form stops for the pin 34 which stops the valve member 14 either in a position to operate as a whistle or as a siren.

The device in its completed form is small, 50 compact, and easily operable either as a whistle or a siren and fulfills the requirements of traffic officers.

Although I have shown and described a specific structural arrangement of parts, 55 nevertheless I am aware that certain parts embodied therein may be modified or refined. I, therefore, reserve the right to all such alterations that come within the scope of the disclosure and essence of the invention.

I claim as my invention:

1. A combination siren whistle comprising: a casing having an air inlet and a whistle aperture; a siren mechanism associated 75 with said casing; and a valve in said casing

operable to conduct air from said air inlet through said whistle aperture or through said siren mechanism.

2. A combination siren whistle comprising a casing having a whistle aperture; a mouth-piece on said casing having a single air inlet; a siren mechanism associated with said casing; and a valve rotatably mounted in said casing and operable upon rotation to open parts for conducting air from said air inlet through said whistle aperture or through said siren mechanism.

3. A device of the character described comprising: a casing having a mouth-piece with an air inlet and a circular portion having a whistle aperture in the wall thereof; a siren mechanism mounted on one end of said circular portion; a valve rotatably mounted within said circular portion; a closure plate detachably mounted on the end of said circular portion opposite said siren mechanism; and means for rotating said valve to open a port for conducting air from said air inlet through said whistle aperture or through said siren mechanism.

4. A device of the character described comprising: a casing having a mouth-piece with an air inlet and a circular portion having a whistle aperture in the wall thereof; a closure plate on one end of said circular portion, said closure plate having a series of apertures therein; a siren mechanism operably associated with said closure plate; a cup-shaped valve rotatably mounted within said circular portion; said valve having a slot in the circular wall thereof communicating with said air inlet and a series of apertures in the transverse wall thereof adapted to register with the series of openings in said closure plate; a second closure plate on said circular portion opposite said first mentioned closure plate; and means for rotating said cup-shaped valve to close the series of openings in said first mentioned closure plate and bring the slot in the circular wall thereof into registration with the whistle aperture to operate as a whistle or to close said whistle aperture and bring the series of apertures in the transverse wall of said valve into registration with the series of openings in said first mentioned closure plate to operate as a siren.

5. A whistle combination of the class described embodying: a housing having a mouth piece and a cylindrically chambered portion, said cylindrically chambered portion having a whistle opening in its cylindrical wall adjacent the mouth piece and a plurality of openings in one side wall thereof; a valve member rotatably mounted in said chambered portion operable to alternatively close said whistle opening and open said side openings; and a siren member on the side containing the side openings.

6. A whistle combination of the class de-

scribed embodying: a housing having a mouth piece and a cylindrically chambered portion, said cylindrically chambered portion having a whistle opening in its cylindrical wall and a plurality of apertures in its side wall; valve means in said chambered portion comprising a cup member rotatably mounted in said chambered portion and having an opening corresponding with said whistle opening and provided with a side member having a plurality of openings adapted to register with the openings in said side member when the whistle opening and the corresponding opening in the cup member are not in registration; and a siren member on the side of said housing having the openings therein.

7. In combination with a whistle mechanism comprising a housing having a mouth piece, a cylindrically chambered portion and a siren mounted on one wall of the chambered portion, a valve embodying: a cup member rotatably mounted in said cylindrical portion and having an opening which registers with the mouth piece, said cup member having a side wall provided with a plurality of openings in the side of said housing carrying said siren; and means for rotating said cup member so as to alternatively open and close the side openings in said housing.

8. A siren whistle embodying: a cylindrically chambered casing having a mouth piece opening into the chamber therein; a siren member mounted on one side of the cylindrically chambered portion of said casing, the side of said casing carrying said siren member being provided with a plurality of apertures; and valve means for optionally establishing communication through said mouth piece and said side apertures comprising a side plate engaging the apertured side of said casing and having apertures therein corresponding to the apertures in the side of said casing, and a curved shield member secured to said side plate and provided with an opening which registers with the opening in said mouth piece when the openings in said side plate and said side member are in registration.

50 In testimony whereof, I have hereunto set my hand at Los Angeles, California, this 17th day of January, 1931.

FRANK WILCOX.
